UNITED STATES PATENT OFFICE.

JOHN W. HOWARD, OF PITTSBURGH, PENNSYLVANIA.

CAN-OPENER.

1,365,405.

Specification of Letters Patent. Patented Jan. 11, 1921.

Application filed August 4, 1919. Serial No. 315,233.

To all whom it may concern:

Be it known that I, JOHN W. HOWARD, a citizen of the United States, residing at Pittsburgh, in the county of Allegheny and State of Pennsylvania, have invented a new and useful Improvement in Can-Openers, of which the following is a full, clear, and exact description, reference being had to the accompanying drawings, forming part of this specification.

This invention relates broadly to can openers and has for its principal object to provide a mechanism comprising a cutting device and a clamping device, wherein such devices may be relatively adjusted vertically and circumferentially to position, puncture and open the can.

Another object of the present invention is to provide a can opener of the type referred to, having several of the parts adjustable to adapt same for use with cans of different heights and diameters.

A further object of the present invention is to provide means for centering, clamping and elevating a can by a single operation to expedite the positioning and opening thereof. A still further object of the present invention is to construct a can opener in which the cutting device may be adjusted circumferentially or radially, and a relative movement in any of said positions may be produced between the cutter and the can to be opened.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a side elevation of my improved can opener, parts thereof being broken away, and

Fig. 2 is a section on the line II-II of Fig. 1.

Referring more particularly to the drawings; I have illustrated a can opener comprising a base 2 of any desired material and configuration, carrying a pair of uprights 3 connected by a suitable cross head 4. The uprights 3 preferably have formed on one face thereof a series of rack teeth 5, and are provided at their lower ends with feet

6 adapted to be secured in any desired manner to the base 2.

Cooperating with the rack teeth 5 are pinions 7 mounted on the transversely extending shaft 8, which is journaled adjacent its opposite ends in the U-shaped guides 9 formed on the cross head 10. A suitable crank 10' may be formed or secured to the shaft 8 for rotating the pinions 7 to elevate the cross head 10 and the mechanism carried thereby to any desired position for the purpose hereinafter to be described.

Journaled in the cross head 10 is a stud shaft 11 carrying at its lower end a bevel gear 12 adapted to be rotated by cooperating with bevel gear 13 suitably actuated by a crank 14. In the preferred embodiment of my invention, the bevel gear 12 carries the cutting member 15, which is radially adjustable for opening cans of different diameters by the screw 16 and operating thumb nut 17. It will be apparent that with the mechanism described it is possible to elevate the cross head to any desired position to permit the insertion of a can C on the base between the uprights and that the cutter is radially adjustable for opening such cans of varying diameters.

I have found that it is desirable to center, elevate and clamp the cans by a single operation. In order to accomplish this result, I may provide the base 2 with radial slots 18, for receiving clamping jaws 19. Rotatably mounted in the bearing 20 below the base, is a plate 21 having eccentric slots 22 formed therein for receiving the downwardly projecting pins 23 carried by the clamping jaws 19. Each of the clamping jaws is preferably provided with an inclined upper can receiving face 24 at the extremity of which there projects upwardly a stop 25. Extending through each of the stops 25 is a spring arm 26 having an enlarged head 27 to limit the movement thereof in one direction, and having an arcuate centering and clamping jaw 28 formed on the opposite end thereof. Intermediate the face of the stop 25 and the back of the centering and clamping jaw 28, on each of the rods 26, is a spring 29. By reason of this construction, it will be apparent that if the plate 21 is rotated in a counterclockwise direction, the jaws 19 will be moved radially inwardly in the slots 18, while if the plate 21 is rotated in the opposite direction, an outward movement of the jaws will result.

110

- If a can is placed in position on the inclined faces of the jaws 19, as illustrated, and the plate 21 is rotated in a counterclockwise direction, the can will ride upwardly 5 on the inclined faces until the head of the can is engaged and perforated by the cutting mechanism. At this time the mechanism may be operated and the head of the can removed.
- 10 If desired, the base of the can opener may be provided with a suitable clamp 30 so that it may be clamped to a table 31, or similar support.
- The advantages of the present invention 15 arise from the construction permitting the proper positioning of the cans by a single operation, and from means provided for easily removing the ends when so positioned.
- 20 I claim:
1. A can opener, comprising a base, uprights carried thereby, a cutting mechanism carried by said uprights, means for simultaneously clamping a can in position to be 25 opened by said cutting mechanism and elevating the same into engagement with the cutting mechanism, and means for producing a relative movement between said clamping means and the cutting mechanism, substantially as described.
2. A clamping device for can openers, comprising a base having radial grooves formed therein, a plate rotatably mounted with relation to said base, and having eccentric slots formed therein, clamping jaws having can supporting and elevating faces 35 slidably mounted in said grooves, and having a projection engaging said slots, and means for rotating the plate to adjust said 40 jaws, substantially as described.

3. A clamping jaw for can openers, comprising a body having an inclined can receiving face, a stop formed on said body, a spring rod slidably mounted in said stop, and a clamping and centering jaw carried by said rod, substantially as described.

4. A can opener, comprising a base, a cutting mechanism carried thereby, a clamping mechanism on said base, said mechanism comprising a series of adjustable jaws having can supporting and elevating faces, and means for adjusting said jaws for simultaneously elevating a can into engagement with the cutting mechanism and clamping the same to prevent rotation thereof, substantially as described.

5. A can opener, comprising a base, a cutting mechanism above the base and carried thereby, a clamping mechanism on said base, said mechanism comprising a series of adjustable jaws having can supporting and elevating faces, and means for adjusting said jaws inwardly to simultaneously elevate the can supported thereon into engagement with the cutting mechanism and clamp the same to prevent rotation thereof, substantially as described.

6. A can opener, comprising a base, a cutting mechanism above the base and carried thereby, a clamping mechanism on said base, 70 said mechanism comprising a series of adjustable jaws having can supporting and elevating faces, resilient clamping and centering means on said jaws and means for actuating said jaws, substantially as described.

In testimony whereof I have hereunto set my hand.

JOHN W. HOWARD.
